(57) CLAIM

I claim the ornamental design for an athletic shoe, substantially, as shown and described.

DESCRIPTION

FIG. 1 is a left side perspective view of the athletic shoe showing my new design;

FIG. 2 is a top elevational view thereof;

FIG. 3 is a bottom elevational view thereof;

FIG. 4 is a right side elevational view thereof;

FIG. 5 is a front side elevational view thereof; and,

FIG. 6 is a back side elevational view thereof.

The broken lines in FIGS. 1-6 are for illustrating portions of the athletic shoe that form no part of the claimed design.
